UNITED STATES PATENT OFFICE.

CHARLES H. CARMER, OF OLEAN, NEW YORK, ASSIGNOR TO CLARK BROTHERS COMPANY, OF OLEAN, NEW YORK, A CORPORATION OF NEW YORK.

NOTCH FINDER FOR POWER SETWORKS.

Application filed July 3, 1926. Serial No. 120,487.

This invention relates to an improvement in notch finders for power set works.

The object of the invention is to provide an attachment for set works which will enable the operator to obtain the proper notch in the quadrant of the set works quickly when changing from one thickness to another, within the limitations of the set works.

10. This invention enables the operator to change quickly to the thickness of lumber desired to be cut and insures of an accurate adjustment of the set works to saw the lumber of this particular size.

15. To accomplish these objects and to obviate the difficulties encountered in the use of the present set works, a plate is attached to one side of the notched quadrant, which regulates the movement of the set lever, which 20 plate has a plurality of holes corresponding to the notches in the quadrant therein for receiving pins. A bracket is attached to the side of the set lever and carries dogs in position to engage the pins in the plate to limit 25 the extent of throw of the set lever. These dogs are pivoted in a suitable manner in the bracket and they are provided with enlarged holes therethrough receiving a pin, 30 smaller in size than the diameter of the hole in order to enable the dogs to rock on their pivots so as to allow the set lever to be moved back or forward without necessitating the lifting of the dogs on the backward movement of the set lever but on the forward 35 movement it is necessary to lift the dogs or raise the pins.

In the accompanying drawings:

Fig. 1 is a side elevation of the power set works, mounted on the saw mill carriage;

40 Fig. 2 is an enlarged side elevation of the set lever and quadrant therefor;

Fig. 3 is a top plan view thereof partly in section;

45 Fig. 4 is a vertical sectional view through the quadrant, showing the set lever in side elevation; and

Fig. 5 is a vertical sectional view through the supporting bracket for the dogs.

50 The numeral 1 indicates a saw mill carriage upon which is located a power set works indicated generally by the numeral

2. A set lever 3 of this power set works controls the movement thereof and the action of the power cylinders 4 to move the set shaft 5 for controlling the extent of 55 movement of the saw mill dogs and the regulation of the thickness of the lumber to be cut. This power set works may be used to set out lumber to be cut in any of the standard sizes, as follows: one inch; one and a 60 fourth inch; one and a half inch; one and three-fourths inch; two inches; two and a half inches; three or four inches.

It is desirable to provide an accurate adjustment of the set lever 3 so as to obtain 65 a precise cut of lumber to within a thirty-second of an inch in thickness. For this purpose, the set lever 3 has a pawl 6 pivoted thereto for engagement with the teeth 7 of a quadrant 8, as clearly shown in Fig. 2. A 70 lock-latch 9, also pivoted to the set lever 3, bears upon the inclined upper edge 10 of this pawl 6 to lock the pawl in engagement with the teeth 7 of the quadrant. Springs 11 and 12 serve to hold the lock-latch in engagement with the pawl and prevent the pawl from slipping out of engagement with the quadrant. 75

Secured to one side of the quadrant 8 and carried by the frame work of the set 80 works 2, is a plate 13, provided with a plurality of holes 14 therethrough for receiving pins 15, as shown in the drawings. A graduated scale plate 16 is secured to one side of the plate 13, as shown in Figs. 3 and 4. 85

A bracket 17 is secured to one side of the set lever 3 by means of set screws 18, as shown in Fig. 4, and this bracket 17 has the arms 19 and 20 thereof extending upwardly in a spaced apart relation. Extending 90 through the arms 19 and 20 is a pin 21 forming the pivotal support for dogs 22, having the front ends 23 thereof extending upwardly, as indicated in Fig. 5. These dogs 22 are positioned between the arms 19 and 20 and have the rear ends thereof provided with enlarged openings 24 for receiving the pin 25, which also extends through the arms 19 and 20, the diameter of which pin is less than the diameter of the orifices 24. Extending upwardly from the arm 19 is a supporting bar 26, which carries a pointer 27 100

in alignment with and positioned above the graduated scale 16 for indicating the extent of adjustment of such set lever.

In operation, the pins 15 are placed at 5 points in the plate 13 at a distance apart equal to the thickness which it is desired to cut the lumber. It is to be noted that the holes 14 correspond with the teeth 7 of the quadrant, and there are the same number 10 of holes as there are teeth in this quadrant, within the same extent thereof. With the pins 15 placed in the proper holes 14 and with the set lever in the position shown in 15 Fig. 2, if the thickness to be cut is at the pin third from the left of Fig. 2, the operator pushes the first two pins up, then moves the set lever 3 to the right, after having moved the lock-latch 9 out of engagement with the pawl 6, allowing said pawl to move 20 out of engagement with the teeth 7, and when this movement of the set lever 3 has been continued until the corresponding dog 22 engages the third pin 15, the set lever is released, allowing the pawl 6 to again engage 25 the teeth of the quadrant and be held in position by the lock-latch 9, while thus setting the set works in the proper position to cut the lumber of the desired thickness.

30 Instead of lifting the pins 15 so as to allow the pawls 22 to pass thereunder, the operator may move the rear ends of these pawls up so that the front ends thereof will pass under the pins 15 to allow the proper 35 setting of the set works on the forward movement of the set lever, but on the backward movement the pawls 22 automatically pass the pins 15.

Upon releasing of the dogs, they will 40 again drop to the position shown in Fig. 5 where they will engage the next succeeding pin in the movement of the set lever. In order to move the set lever back into a further and next succeeding position, all that 45 is necessary is to disengage the pawl 6, the dogs 22 being allowed to move about their pivot pin 21, as the backs of the ends thereof engage the pins 15, until the set lever has been moved back to its proper set position with the dogs engaging the back of 50 the proper pin 15. The size of the holes 24 and pin 25 regulate this pivotal movement, and due to the position of the pivot pin 21 the dogs will always move down 55 again in position to engage the pins 15.

I claim:—

1. In a device of the character described, the combination with a set lever, and quadrant therefor, of a plate extending laterally from said quadrant and having a plurality of holes therein, pins extending into the holes, and means connected with the set lever for engaging the pins.

2. In a device of the character described, 60 the combination with a set lever, of a plate

associated with said lever and having a plurality of holes therein, a pin extending into one of the holes, a bracket carried by the set lever, and a pawl carried by said bracket for engaging the pin. 70

3. In a device of the character described, the combination with a set lever, of a plate associated with said lever and having a plurality of holes therein, pins extending into the holes, a bracket carried by the set lever, 75 and pawls pivotally mounted in the bracket and movable into and out of position for engaging the pins.

4. In a device of the character described, the combination with a set lever and quadrant therefor, of a plate extending laterally from said quadrant and having a plurality of holes therein, pins extending into the holes and means connected with the lever and movable into and out of position for 80 engaging the pins.

5. In a device of the character described, the combination with a set lever and quadrant therefor, of a plate extending laterally from said quadrant and having a plurality of holes therein, pins extending outwardly from the holes and removably positioned therein, a bracket carried by the set lever, and means carried by said bracket movable 90 into and out of position for engaging the pins.

6. In a device of the character described, the combination with a set lever and quadrant therefor, of a plate extending laterally from said quadrant and having a plurality of holes therein, pins extending outwardly from the holes and removably positioned therein, a bracket carried by the set lever, and dogs pivotally mounted in the bracket 100 for movement into and out of position for 105 engaging the pins and limiting the extent of movement of the set lever.

7. In a device of the character described, the combination with a set lever and quadrant therefor, of a plate extending laterally from said quadrant and having a plurality of holes therein, pins extending outwardly from the holes and removably positioned therein, a bracket carried by the set lever, and dogs pivotally mounted in the bracket 110 for movement into and out of position for 115 engaging the pins and limiting the extent of movement of the set lever, said dogs having enlarged openings therein at one side of the pivots therefor, and a pin extending into 120 the openings and connected with the bracket for limiting the pivotal movement of the dogs.

8. The combination with a set lever, a notched quadrant associated therewith, and 125 a pawl carried by the set lever in position to engage the notched quadrant, of a plate extending laterally from the quadrant and having a plurality of holes therein, pins 130 removably extending through the holes, a

bracket carried by the set lever, dogs pivotally mounted within said bracket and having the ends thereof projecting upwardly in position to engage the pins, a pivot pin for the dogs, said dogs having enlarged openings therein eccentrically positioned relative to the pivot pin, a pin extending into said openings, of a diameter less than that of the

openings, for limiting the pivotal movement of the dogs, a graduated scale connected with a plate and a pointer extending upwardly from the bracket in position to cooperate with said scale. ¹⁰

In testimony whereof I affix my signature.

CHARLES H. CARMER.
